UNITED STATES PATENT OFFICE

2,046,608

METHOD AND APPARATUS FOR BENDING
RIBBED SHEET METAL FLASHINGSAllan Cheney, Melrose, Mass., assignor to The
Cheney Company, a corporation of Massachusetts

Application August 8, 1933, Serial No. 684,283

15 Claims. (Cl. 153—16)

The present invention relates to improvements in the method and apparatus for forming counter flanges and interlocking wall flashing, and aims generally to improve both existing methods and apparatus therefor.

Interlocking wall flashings, as used in modern masonry structures comprises a sheet of metal, preferably copper, of desired width to extend entirely through the wall of a masonry structure so as to cut off the downward seepage of water that infiltrates into the wall. The flashing sheet is embedded in a layer of mortar of the wall structure and as mortar does not bond or adhere to sheet metal, the flashing sheet is deformed to provide dovetail-like ribs and recesses into which the mortar may be molded so as to provide a mechanical bond between superposed courses of masonry, and advantageously may be of the types and construction shown in the Cheney Patents Nos. 1,715,000 and 1,871,585. In many instances the flashing sheet is formed with a counter flange, as for example, when used above a roof line or in conjunction with a base flashing, as shown in the Cheney Patents Nos. 1,728,955 and 1,868,092.

Advantageously the ribs and grooves of the flashing sheet extend transversely of the sheet as shown in the Cheney Patent No. 1,715,000, dated September 24, 1929, and No. 1,871,585 dated August 16, 1932, so as to provide a maximum number of interlocking keys with the mortar above and below the sheet, the grooved portions, on the upper surface of the flashing sheet, constituting drainage areas to permit a free unobstructed draining of the water of infiltration outwardly from said walls.

Heretofore in the manufacture of wall flashings, and particularly when bending the counter flange thereon, the metal of the sheet between the ribs, and which forms the drainage grooves, during the bending, is distorted upwardly or in a direction opposite to the direction of bend for the counter flange, thus in effect forming a dam across the drainage grooves, and seriously preventing the free drainage of water of infiltration from the wall.

With these problems in view, my present invention aims to improve existing methods and apparatus as well as the flashing itself, by bending the marginal edge portions of the sheet to form the counter flange, while clamping the opposite surfaces of the sheet constituting the drainage grooves against deflection or distortion, so that the drainage surfaces of the grooves of the finished flanged flashing sheet will lie in a symmetrical

horizontal plane, and be free from distortion such as would constitute a dam against the free drainage of water from said grooves.

With these and other objects in view reference may be had to the accompanying drawings which are explanatory of preferred forms of the method as well as exemplifying a suitable apparatus for practicing the method.

In the drawings—

Fig. 1 is a perspective view of one form of interlocking wall flashing capable of being bent according to my invention; 10

Fig. 2 is a perspective view of another form of interlocking wall flashing that may be bent according to the invention. 15

Figs. 3, 4 and 5 are detail diagrammatic views illustrative of successive steps in the forming of the counter flange according to the present invention;

Fig. 6 is detail diagrammatic views illustrating modified forms of the method and apparatus according to the present invention; 20

Fig. 7 is a front elevation of one form of apparatus for practicing the method;

Fig. 8 is an end view thereof;

Fig. 9 is an enlarged sectional view taken on the line 9—9 of Fig. 7; and

Fig. 10 is a detail sectional view taken on the line 10—10 of Fig. 7. 25

In the bending of the counter flange in interlocking wall flashing, according to the present invention, a sheet of metal, such as copper, previously deformed to provide interlocking ribs and grooves, such as the dovetail ribs and grooves of the flashing shown in Fig. 1, or the saw-tooth dovetail ribbed construction of Fig. 2, is placed in a suitable bending machine, the material being clamped in position in the machine by means of filler blocks F, or the like, engaging in the grooved portions of the sheet which constitute the water drainage grooves G, and a clamping bar C. The filler blocks F advantageously are of a size and shape to correspond to the cross section of the grooves G, so that when the sheet is clamped in position as shown in Fig. 3, distortion of the metal of the grooves, in the region of the bending point, will be prevented. The clamping face of the bar C is plain (see Fig. 7) so that only the groove portions of the flashing are clamped. 30

With the initial flashing sheet so clamped, a bending plate B is rotated about the pivotal axis P, to bend the sheet metal above it, to form an angular bend on the marginal edge of the flashing sheet. Preferably this bending includes movement of the marginal edge of the sheet through 45

an angle of 90° so that a right angled counter flange is formed on the sheet (see Fig. 5).

The bending plate B obviously engages the depending rib portions of the flashing intermediate the clamped groove portions (see Figs. 3 and 4) so that the metal of the unclamped rib portions, below the clamping bar c may gradually slope toward the bend (see Fig. 5), making possible a more satisfactory bend.

10 In many cases it is desirable that the ribs of the counter flange be flattened to reinforce the flange and instead of effecting this flattening of the ribs in a separate pressing operation, as is customary, the flattening of the ribs may take 15 place simultaneously with the forming of the counter flange. In order to accomplish this flattening (see Fig. 6), the clamping bars may be formed or provided with a vertical face C' along the face of the clamp C which is adjacent to the 20 vertical plane of the bending point P. As will be apparent, this face C' will act as a backing or abutment against which the ribbed counter flange may be pressed during the final movement of the bending bar B, so as to flatten the 25 ribs of the counter flange into reinforcing or stiffening plaits. A suitable apparatus for carrying out the method and which comprises one preferred embodiment of the invention is illustrated in Figs. 7 to 30 10 inclusive.

According to the invention, end frames 10, which may comprise spaced angle iron uprights 11 connected at the lower ends by foot portions 12 are rigidly connected together by a bed 13 and tie-rod 14. The bed 13 (see Fig. 9) may be advantageously constructed of T-iron, as shown, and is arranged to support the flashing material to be bent, adjacent the bending point. A table 15 arranged to support the body of the material 40 is pivotally connected, as at 16, to the bed 13 and is supported in a horizontal position, in the plane of the top of the bed 13, by means of legs 17 pivoted to the outer edge of the table and notched as at 18 to engage a cross bar 19 connected to 45 the opposite foot portions 12, the arrangement permitting the table and legs to be folded, one upon the other, and to be closely folded with relation to the end frames 10, as will be apparent. Advantageously the table is provided with a stop 50 or gauge 20, adjustably clamped to the table and serving to act as a limiting stop, against which the flashing material fed into the machine from the front, may abut, to accurately gauge the width of flange to be bent.

55 In order to maintain the drainage groove portions of the ribbed flashing sheet against deflection during bending, such as would form a dam against the free drainage of water from the flashing sheet, the bed 13 is preferably provided with a plurality of filler blocks 21 (see Fig. 9) which may be adjustably clamped as by screw bolts 22 in a guideway 23 formed or secured to the bed 13. These filler blocks are of a size and shape substantially to fill the grooved portions of the flashing sheet, and preferably during the bending operation the groove portions of the sheet is clamped between the filler blocks 21 and a clamping bar 24 vertically movable to engage the upper surface of the sheet, to clamp the sheet at the groove portions only against movement and the drainage surface of the grooves against deflection or distortion during the bending of the counter flange. Advantageously the clamping bar is 60 in the form of a T-bar having a plain straight

clamping face (see Fig. 7) and having the flanges cut away adjacent the ends as at 25 to provide end extremities 26 comprised of the vertically disposed webs of the bar which are adapted to extend between the spaced uprights 11 for connection to operating means comprising a connecting rod 27 pivotally connected as at 28 to a treadle 29 pivoted to the base of the machine, as for example, to the bar 19. A spring 30 connected to the treadle 29 and the end frames 10 acts normally to hold the treadle and clamping bar 24 in raised or unclamped position.

The bending plate B advantageously may be in the form of an angle bar 32 of suitable shape, replaceably secured, in any desired manner, to a 15 carrier 33, hanging in opposed hangers 34, which in turn, may be pinned as at 35 to shafts or rocking arms 36 journaled in the end frames 10, and provided at their outer extremities with operating handles 37, outwardly beyond the end frames. 20 Conveniently, additional operating handles 38 may be secured to the bending plate carrier between the end frames, as by suitable fastenings 39, for the convenience of the operator.

Preferably the bending plate carrier 33 is ad- 25 justable in the hanger 34 so as to vary the degree of compression of the rib portions in the region of the bend or throughout a substantial distance across the counterflange. As will be apparent, if it is desired to compress or flatten the rib por- 30 tions tightly to reinforce the counterflange, the bending plate 32 must be slightly higher (as viewed in Fig. 9) than would be the case if a more or less open bend and ribbed counter flange is desired. This is accomplished in the illustrated 35 embodiment by bolting the carrier 33 to the hanger 34, as at 40, the bolts passing through elongated slots 41 in the carrier, so that adjustment of the carrier 33 with respect to the hangers 34 may be effected. This adjustment may be facil- 40 itated by means of adjusting screws 42 and lock nuts 43 in the lower ends of the hanger so as to accurately adjust the vertical height of the bending plate preparatory to clamping it in ad- 45 justed position upon tightening of the bolts 40.

In the embodiment of the invention shown in Fig. 6, the clamping plate is provided with a vertical backing face C', and advantageously this may be removably secured to the clamping plate by means of suitable fastenings, such as bolts 44. 50 With such construction and with the bending plate in its uppermost adjusted position, the ribbed portions of the flashing will be tightly flattened across the counterflange.

Assuming that it is desired to form a counter 55 flange on a transversely ribbed dovetail sheet metal as shown in Fig. 1, the sheet of metal is laid upon the bed or table with its upper face down, the filler blocks having been previously ad- 60 justed along the guideway 23 to be accurately positioned in the groove portions of the sheet, there being one filler block for each groove. The operator then clamps the sheet in position by pressing the treadle 29 causing the clamping bar 24 to be lowered to clamp the groove portions of 65 the sheet securely in position between the clamping bar and the filler blocks. The bending plate B may then be rotated about its pivot P due to movement of the hand levers 37 and 38, to bend the unclamped marginal edge of the sheet ma- 70 terial upwardly about the pivot point P (see Figs. 4, 5 and 6). The bending plate obviously engages the depending rib portions of the sheet inter- 75 mediate the clamped groove portions and permits of the tapering of the metal of the rib ad-

5 jacent the bend so as to facilitate in making an accurate and sharp bend. The surface of the material which lies against the filler blocks F will, in use, constitute the bottom of a drainage groove of the flashing and because it is clamped securely between opposed clamping surfaces 21 and 24 during the bending operation, there will be no distortion of the surface and hence free drainage of water of infiltration into the wall be insured.

10 Among the advantages of the invention is the improved character of flashing material that is produced by it, namely, that the bottoms of the drainage grooves are free from distortion. The machine is simple in construction and may easily be transported from place to place and set up for use on the job, and when the filler blocks are shaped and adjusted for any particular type and construction of flashing, suitable bends or flanges 15 may be produced on the ribbed flashing expeditiously and economically.

Having described my invention I claim as new:

20 1. The method of forming a counter flange on ribbed sheet metal flashing sheets and the like such as is formed with a plurality of alternate ribs and water drainage grooves, which comprises clamping the groove portions of the underside of said sheet on opposite sides adjacent the plane of the bend, leaving intermediate unclamped rib 25 portions, and applying a bending pressure to the rib portions throughout a marginal edge portion of said sheet.

25 2. The method of forming a counter flange on ribbed sheet metal flashing sheets and the like such as is formed with a plurality of alternate ribs and water drainage grooves, which comprises clamping the sheet between opposed clamping surfaces at spaced points throughout the length of the sheet and applying a bending pressure to 30 the unclamped intermediate portions.

30 3. The method of forming a counter flange on ribbed sheet metal flashing sheets and the like such as is formed with a plurality of alternate ribs and water drainage grooves, which comprises clamping the sheet between opposed clamping surfaces at spaced points throughout the length 35 of the sheet and applying a bending pressure to the unclamped intermediate portions in a plane spaced from the plane of said clamped portions.

35 4. The method of forming a counter flange on sheet metal through-wall flashing of the type having a series of alternate transverse ribs and water drainage grooves, which comprises applying a bending pressure to a surface of the rib 40 portions of said sheet while clamping the opposite surfaces of the intermediate groove portions against deflection or distortion whereby to confine the drainage surfaces of said grooves in a symmetrical plane, free from upward bulging 45 such as would retard draining of water from the surface of said grooves.

50 5. The method of forming a counter flange on sheet metal through-wall flashing of the type having a series of alternate transverse ribs and water drainage grooves, which comprises applying a bending pressure to a surface of the rib 55 portions of said sheet while clamping the opposite surfaces of the intermediate groove portions against deflection or distortion whereby to confine the drainage surfaces of said grooves in a symmetrical plane, free from upward bulging 60 such as would retard draining of water from the surface of said grooves, the bending pressure being initially applied in a plane spaced from the 65 plane of the clamped groove portion.

6. A machine for bending a counter flange on ribbed material having a plurality of alternate ribs and grooves such as through-wall flashing, comprising a bed, a plurality of positioning means on said bed adapted to be positioned in groove 70 portions of said material, clamping means for engaging the groove portions of said material so that said groove portions are clamped between said positioning and clamping means, and means for applying a bending pressure to a rib portion 75 of said material throughout a marginal edge portion thereof to bend said edge portion to an angular position with respect to the body of said machine.

7. A machine for bending a counter flange on ribbed material having a plurality of alternate ribs and grooves such as through-wall flashing, comprising a bed, a plurality of positioning means on said bed adapted to be positioned in groove 80 portions of said material, clamping means for engaging the groove portions of said material so that said groove portions are clamped between said positioning and clamping means, the intermediate rib portions of said material being unclamped, and means for applying a bending pressure 85 to a rib portion of said material throughout a marginal edge portion thereof to bend said edge portion to an angular position with respect to the body of said material.

8. A machine for bending a counterflange on sheet metal wall flashing of the type having alternate ribs and grooves, comprising a bed, spacing blocks on said bed adapted to be positioned in said grooves and conforming substantially to the cross section, a clamping bar for engaging the 90 opposite surface of said flashing and cooperating with said spacing blocks to clamp the groove portions of said flashing against deflection, and a bending bar having a portion in engagement with the rib portions of said flashing for bending 95 a marginal flange portion of said material to an angular position with respect to the body thereof.

9. A machine for bending a counterflange on sheet metal wall flashing of the type having alternate ribs and grooves, comprising a bed, spacing blocks on said bed adapted to be positioned in said grooves and conforming substantially to the cross section, a clamping bar for engaging the 100 opposite surface of said flashing and cooperating with said spacing blocks to clamp the groove portions of said flashing against deflection, and a bending bar pivoted to the bed of the machine and having a portion in engagement with the rib portions of said flashing for bending a marginal flange portion of said material to an angular 105 position with respect to the body thereof.

10. A machine for bending a counterflange on sheet metal wall flashing of the type having alternate ribs and grooves, comprising a bed, spacing blocks on said bed adapted to be positioned in said grooves and conforming substantially to the cross section thereof, a clamping bar for engaging the opposite surface of said flashing and cooperating with said spacing blocks to clamp the groove portions of said flashing against deflection, and a bending bar pivoted to the bed of the machine in a plane spaced from the plane of the clamped groove portions of the flashing and having a portion in engagement with the rib portions of said flashing for bending a marginal flange portion of said material to an angular 110 position with respect to the body thereof.

11. A machine for bending a counterflange on sheet metal wall flashing of the type having alternate ribs and grooves, comprising a bed, spac-

- ing blocks on said bed adapted to be positioned in said grooves and conforming substantially to the cross section thereof, a clamping bar for engaging the opposite surface of said flashing and cooperating with said spacing blocks to clamp the groove portions of said flashing against deflection, an upwardly swinging bending bar pivoted to the bed at a plane below the plane of the clamped groove portions having a portion in engagement with the rib portions of said flashing for bending a marginal flange portion of said material to an angular position with respect to the body thereof.
12. A bending machine of the character described comprising a bed plate, a supporting table at one side of the bed plate, means mounted upon said bed plate for supporting and positioning ribbed sheet metal of corrugated dovetail shaped configuration, said means adapted to be positioned within the groove portions of said sheet, clamping means cooperating with the sup-

porting and positioning means for clamping the groove portions of said metal sheet in position with its groove surface supported and clamped against deflection, and means acting upon the rib portions of the material intermediate the clamped groove portions for bending a portion of the sheet transversely of the ribs thereof and about a plane adjacent the clamped portion thereof.

13. A bending machine as defined in claim 12 further characterized by the provision of a plurality of supporting and positioning means adjustably mounted in a slotted guideway.

14. A bending machine as defined in claim 12 further characterized by the provision of means for adjusting the plane of the bending pivot.

15. A bending machine as defined in claim 12 characterized by the provision of a backing plate against which the bent marginal edge of the material may be flattened.

ALLAN CHENEY. 20
